UNITED STATES PATENT OFFICE.

MORTEN S. JOHNSON, OF CHICAGO, ILLINOIS.

PIN-TICKET.

SPECIFICATION forming part of Letters Patent No. 748,957, dated January 5, 1904.

Application filed October 13, 1902. Serial No. 126,984. (No model.)

To all whom it may concern:

Be it known that I, MORTEN S. JOHNSON, a citizen of the United States, and a resident of Chicago, in the county of Cook and State of Illinois, have invented a Pin-Ticket, of which the following is a specification.

This invention relates to pin-tickets for marking merchandise, as clothing, fabrics, and the like.

10 Primary objects of my invention are to provide a pin-ticket of simple and cheap construction, which may be quickly and conveniently attached to and detached from the goods to be marked; to provide a pin-ticket 15 which may be manipulated without danger of pricking the fingers on the pin-points, and to prevent the pin-points from pricking the hands and catching in the goods in handling.

To this end a pin-ticket of my invention 20 consists of the various features, combination of features, and details of construction hereinafter described and claimed.

In the accompanying drawings a pin-ticket of my invention is fully illustrated.

25 Figure 1 is a perspective view of a pin-ticket of my invention. Fig. 2 is a sectional view thereof inserted through a piece of cloth. Fig. 3 is a similar view showing the pins bent down to secure the ticket to the cloth, and 30 Fig. 4 is a plan view showing the ticket attached to a piece of cloth.

Referring now to the drawings, 1 designates the ticket, and 2 flexible pins rigidly secured thereto. The ticket may be of any 35 usual or desired construction, and the pins 2 may be secured thereto in any manner desired. As shown, the ticket 1 consists of two layers or pieces of paper pasted together, one of said pieces being preferably made of 40 card-board. As shown, also, the pins 2 are formed from an integral piece of wire, the connecting or intermediate portion 3 of which is bowed or U-shaped and is bent laterally relatively to said pins, so that said pins 2 and 45 said curved or U-shaped section 3 will be in different planes. The curved or U-shaped section 3 is secured between the layers of the ticket 1, the pins 2 passing through one 50 layer of said ticket and projecting laterally therefrom. It is obvious that the curved or

U-shaped portion 3 of the wire forming said pins 2 will secure said pins rigidly to the ticket 1. The ends of the pins 2 are bent to form hooks 4, said hooks being preferably bent slightly beyond a position at right angles to the body portions of said pins. When the ticket is finished and ready for use, the pins 2 extend substantially at right angles to the surface of said ticket.

In attaching the ticket the pins 2 are inserted through the goods 5, preferably until the ticket 1 is in contact with said goods. Said pins are then bent down bodily upon the goods in such a manner that the hooks 4 will enter the goods, thereby firmly securing 65 said ticket to the goods. Preferably, also, the pins 2 project from the surface of the ticket 1 a distance less than that between the points where they leave the ticket and the side or end of said ticket in the direction in 70 which they are to be bent. Thus, when said pins are bent over in attaching said ticket, the ends of said hooks will strike and be covered by said ticket, insuring against their catching in other goods in handling or pricking 75 the hands. In bending said pins, also, the pressure will be exerted on the opposite sides thereof from the hooks 4, thus insuring against pricking the fingers in bending said hooks, as often happens in bending straight 80 hooks.

The meaning or significance of the word "hook," as used herein, is that the ends 4 of the pins 2 are bent at such angles relatively to the shanks thereof that they will catch in 85 the fabric when drawn across the same.

I claim—

1. A pin-ticket consisting of a ticket and pins for insertion through the fabric rigidly secured to and projecting from said ticket at 90 a distance from the edge thereof toward which said pins are designed to be bent, said pins being bent at their ends to form hooks for engagement with the fabric at a distance from the point where said pins pass through 95 the same, substantially as described.

2. A pin-ticket consisting of a ticket and pins for insertion through the fabric rigidly secured to said ticket at a distance from the edge thereof toward which said pins are de- 100

signed to be bent greater than the length of
said pins, said pins being bent at their ends
to form hooks for engagement with the fabric
at a distance from the point where said pins
5 pass through the same, substantially as de-
scribed.

In testimony that I claim the foregoing as

my invention I affix my signature, in pres-
ence of two subscribing witnesses, this 3d day
of October, A. D. 1902.

MORTEN S. JOHNSON.
